(57) **CLAIM**

The ornamental design for a fan and light combination, as shown and described.

DESCRIPTION

FIG. 1 is a perspective view of a fan and light combination showing my new design;

FIG. 2 is a front view thereof;

FIG. 3 is a top view thereof;

FIG. 4 is a perspective view of the fan and light combination of FIG. 1 shown in a position of use;

FIG. 5 is a front view thereof;

FIG. 6 is a bottom view thereof;

FIG. 7 is a perspective view of the fan and light combination of FIG. 1 shown in another position of use;

FIG. 8 is a front view thereof; and,

FIG. 9 is an enlarged view of the selected portion in FIG. 1. The broken lines shown in the drawings depict portions of the fan and light combination in which the design is embodied that form no part of the claimed design.
